UNITED STATES PATENT OFFICE

FRITZ APPELIUS, OF BERLIN, GERMANY, ASSIGNOR TO TELEPHON-APPARAT-FABRIK
E. ZWIETUSCH & COMPANY, OF BERLIN-CHARLOTTENBURG, GERMANY

TELEPHONE SYSTEM

Application filed June 27, 1928, Serial No. 288,679, and in Germany July 29, 1927.

The present invention relates in general to automatic telephone systems, but is concerned more particularly with a small sub-exchange working in conjunction with a main exchange. The number of subscribers' lines in the type of sub-exchange above referred to would consist of approximately ten to twenty-five lines and would probably be located in an apartment building or a club-house.

One of the features of the present invention concerns an arrangement for ringing the desired station in the sub-exchange from the main exchange. Talking battery for the subscribers in the sub-exchange is fed from a local battery, which is separated from the main exchange battery, because the line resistance of the main exchange trunk would possibly be too great to provide a good talking circuit for the local subscribers in case talking battery was supplied from the main exchange. The battery of the sub-exchange and that of the central or main exchange are separated by condensers so as not to interfere with each other. Moreover, the main exchange should have the two wires of the trunk line at its disposal for signalling and monitory purposes, without being influenced by the condition of a subscriber's line. The condensers and the talking battery which are connected to the trunk line at the sub-exchange are a hinderance when the operator desires to ring back over the trunk line. The present arrangement, however, shows how to overcome this hinderance.

In a small system of this type, it is often necessary to ring back over the main exchange trunk line in order to connect a subscriber with another subscriber of the same sub-exchange. It is desirable that the calling subscriber engage an exchange line and that the connection to the other subscriber be established over the same exchange line so that two lines are not required for the back calls. Operated in this way, however, makes the sending out of the ringing current even more difficult than described above because the line of the calling subscriber remains connected to the exchange line when it is necessary to ring back on a line. Accordingly, a switch-

ing device, which is switched on by the ringing current from the main exchange, directly connects the subscriber's line to the main exchange trunk and, at the same time, disconnects the disturbing battery bridge circuit at the sub-exchange.

Another feature of the invention relates to the means by which different kinds of subscribers' lines, which have access to the same main exchange trunk line for setting up calls, transmit different kinds of signalling current to the main exchange to operate different signals thereat in order that the calls may be dealt with in an appropriate manner. For example, ordinary subscribers' lines and subscribers' lines having coin box instruments terminating in a sub-exchange have access to the same main exchange trunk line for extending calls. Since both types of sub-exchange subscribers use the same trunk line to the main exchange, some means of signalling is required in order for the operator to discriminate between the different types of subscribers.

Since the sub-exchange is not large enough for the different types of subscribers' lines to be grouped in separate groups, the means for giving the different kinds of signals are, therefore, located in the circuits which are associated with the subscribers' lines.

It is customary in telephone practice to inform the calling party when a connection has been established to a line which is not connected up or which has been disconnected. The known arrangements for signalling the calling party in case the called line is disconnected would be too expensive to be applied to a small system of this type. According to a further feature of the invention, suitable means is provided for signalling the calling party in case the calling party calls a line which is out of service.

In the drawings, comprising Figs. 1 and 2, there is shown by means of the usual circuit diagrams sufficient of the apparatus to enable the invention to be explained and understood.

Referring to the drawings, the apparatus shown at the left of the first dotted line of Fig. 1 is located in the main exchange, while

the remaining portions of Fig. 1 and Fig. 2 are located in the sub-exchange.

The trunk, comprising conductors a and b , extends from the sub-exchange and terminates in the main exchange in jacks VKl and WKl . The jack VKl is used for talking purposes, while the jack WKl is used for dialling purposes. Just above the jacks there are shown the usual double plug ended 10 cord circuit terminating in the plugs ASt and VSt and the single plug and dialling cord WSt .

Sections 2, 3 and 4 of Fig. 1 show a sub-exchange for semi-automatic working with 15 17 subscribers' lines, 11 to 27, inclusive, of which only the lines of subscribers 11, 17, and 27 are shown. The subscribers' lines shown have access to a common trunk comprising conductors a and b extending to the 20 main exchange. The station 27 is a coin box station and, therefore, its individual circuit is slightly different from subscribers' stations 11 and 17. All of the coin box stations have the common relay M connected in series 25 with the second winding of the associated line relay.

Fig. 2, which should be placed directly below Fig. 1, shows a relay counting or selecting switch and other relay circuits located 30 in the sub-exchange.

In order to facilitate the ordinary reading of the circuits, the course of the currents is divided into seven fields; e. g., $4/M$ signifies the relay M in field 4 and $7/k$ 111 represents the contact k 111 in field 7.

Outgoing connection

(1) Subscriber No. 11 takes up the receiver. $T 11$ responds:

40 Earth, $4/h$ II, d III, ab III, $3/t$ 11 I, subscriber's loop, t 11 III, $T 11$, battery.

$3/t$ 11 II closes, before t 11 I and t 11 III open.

$4/D$ responds:

45 Battery, $3/T$ 11 II, t 11 II, $4/d$ 1V, ab II, D , ab I, earth.

$4/d$ II grounds the c wire, $4/d$ 1V opens the short circuit over Ab I, so that Ab responds.

50 $4/d$ III and $4/ab$ III open the starting circuit.

(2) The battery feed relay $3/R$ responds:

Battery, $3/R$, n III, $3/t$ 11 III, subscriber's loop, t 11 I, n I, choke coil $Dr1$ III, earth.

55 $4/r$ III again grounds the c wire and opens the short circuit over the D relay.

(3) $2/r$ I closes the circuit:

Battery, $2/r$ I, m II, k I, a wire to main exchange, b II, at I, MAR , AR , earth.

60 AR and MAR respond.

(4) In the main exchange ar II energizes the visible calling signal ASZ while MAR is at this time without effect.

(5) The operator in the main exchange inserts an answering plug in the jack VKl . A

jack off-normal contact kl applies ground over the B relay to the b wire in order to energize the J relay in the sub-exchange.

The relay B with its b II contact cuts off relay AR so that the visible signal ASZ becomes de-energized.

(6) In the sub-exchange the relay J responds, battery, J , b -wire to exchange, at III, contact kl , B , earth.

$2/j$ II energizes H .

Earth, $2/j$ II, H , battery.

$4/h$ II grounds the c -wire once more for the correct succession during the later release.

$2/h$ I prepares the dialling circuit, $5/h$ III (Fig. 2) prepares the relay selector.

$6/K$ II responds over:

Earth, $6/h$ IV, u III, d I, p II, K II, battery.

$2/k$ I and $2/k$ II switch through the speaking wires in the sub-exchange.

Condition of the group station when the operator answers:

The following relays are energized: T 11, D , Ab , R , J , H , K .

(7) The operator answers in the usual way by means of the answering key A thereby connecting her headset connecting plug.

(8) The battery of the sub-exchange is only put in demand slightly as no selectors are to be positioned. Therefore even dry cells may be used.

(9) Release of the group station.

The subscriber 11 hangs up the receiver. R retracts $4/r$ III short-circuits D , which also retracts. $2/r$ I closes the following circuit:

Battery, $2/r$ I, $Dr1$ II, n II, k I, a wire, jack and plug to signal relay SZ , earth.

When the clearing signal is given the operator withdraws the plug.

(10) In the sub-exchange J retracts when the operator draws the plug. The following operations are due to the fact that a retraction of the J relay is equivalent to a number impulse. Thus first of all comes the number impulse, then the release.

U responds:

Earth, $2/j$ II, h I, st I, U , battery.

$E1$ (Fig. 2) responds:

Battery, $1/sp$ I, u II, $E1$ I, p I, $5/zh$ III, v III and h III, earth.

$E1$ II is connected:

Earth, $5/h$ III, v III, zh III, $1/e$ 1 I, $E1$ II, $5/g$ III, P , battery.

P responds. JC responds:

Earth, $5/h$ III, v III, zh III, $1/JC$ II, u II, sp I, battery.

Now the following relays are attracted: T 11, Ab , H , U , $E1$, P , JC .

By responding, U releases K over u III.

(11) After a period of delay H retracts. $4/h$ II opens the holding circuit for T 11, $5/Ab$ II is further held over $5/jc$ III.

$5/h$ III opens the holding circuit for $E1$. JC and P go back to normal. With con-

siderable delay through the short circuited winding 6 J C I, JC retracts. 2/h I opens the circuit of U, which retracts. After a delay Ab retracts as the last relay. Now the sub-exchange line is again free.

5. *Connection to the subscriber "17"*

(12) The operator inserts the dialling plug in the selecting jack WK1. Through the *a* spring AT is energized thereby connecting the *b* wire to the dialling jack. J responds in the sub-exchange:

Battery, J, *b*-wire, at III, *b*-spring in the dialling jack, dialling plug W-ST, dial switch N Sch, earth.

10. (13) In the sub-exchange, H responds:
Earth, 2/j II, H, battery.

15. 4/h II opens the starting circuit for blocking connections from the sub-exchange to the central office.

(14) Tens selection. First pause in the current impulses: J retracts, U is energized:

Earth, 2/j II, h I, st I, U, battery.

20. JC and E1 respond:

Earth, 5/h III, v III, zh III, 1/p I, E1 I and JC II, u II, sp I, battery.

JC remains energized during the numerical selection by means of the short circuit winding 6/JCI and 5/jc III holds Ab II attracted.

E1 connects itself:

Earth, 5/h III, v III, zh III, 1/e 1 I, E 1 II, 5/g III, P, battery.

25. P responds, 1/p I cuts off E 1 I winding.

(15) First closure in the number switches. J again responds. U retracts, because 2/j II opens the energizing circuit. St responds.

30. 40. Battery, 1/St I, g I, u I, p I, 5/zh III, v III or p II, h III, earth.

(16) End of the tens selection.

During the pause between tens and units selection, J remains energized and U retracted.

45. Therefore in the sub-exchange the relay 1/JC retracts, because 1/u II opens the energizing circuit for sufficient time.

(17) Now Z 1 responds.

50. 48. Earth, 5/h III, v III, 6/p III, jc II, WW II, e1 II, Z 1 I, battery.

Z1 connects itself.

Earth, 5/h III, v III, 6/z1 I, Z1 II, ZH, battery.

55. ZH responds: 5/zh III opens the holding circuit for E 1, St and P, so that P retracts with retarded action.

5/WW responds:

50. 52. Battery, 5/WW, 6/zh I, p III, 5/v III, h III, earth.

WW connects itself over 5/wv I.

Condition in the sub-exchange: relay J, H, Z1, ZH, WW are energized.

60. (18) Units selection "7".

First numerical selection interrupter in the number switch.

J retracts; U responds.

Earth, 2/j II, h I, st I, U, battery.

JC, E1 and Ab II respond:

Earth, 5/h III, v III, ww I, zh III, 1/JC, 70 II, u II, sp I, battery.

Earth, 5/h III, v III, ww I, zh III, 1/p I, E1 I, u II, sp I, battery.

Earth, 5/jc III, Ab II, battery.

E 1 connects itself.

Earth, 5/h III, v III, ww I, zh III, 1/e 1 I, E 1 II, 5/g III, P, battery.

P responds.

(19) First closure of circuit in dial switch. 80 J again responds. U retracts. JC does not let the armature retract as it is slow acting.

St responds.

Battery, 1/St I, g I, u I, p I, 5/zh III, 85 ww I, v III, h III, earth.

The following relays are now energized

Ab, J, H, Z1, ZH, WW (JC) E 1, P, St.

(20) Second interruption of impulse current. 90

J retracts. St II is held and G energized:

Earth, 2/j II, h I, st I, St II, G I, battery. G connects itself over:

Battery, 2/G II, 1/g I, u I, p I, 5/zh III, 95 ww I, v III, h III, earth.

E2 responds.

Battery, 1/sp I, g II, st II, E2I, e 1 I, 5/zh III, ww I, v III, h III, earth.

(21) Second closure of current. 100

J again responds. St retracts, because the winding 1/St I is opened at g I and the winding 2/St II at j II.

E 1 retracts, because the holding current for E 1 II is interrupted at 5/g III (energized) and at st III (at rest). 105

The following relays are energized:

AB, J, H, Z1, ZH, WW, (JC) P, G, E 2.

(22) Third interruption.

J again retracts. U responds. 110

Earth, 2/j II, h I, st I, U, battery.

1/u I opens the holding circuit for G II so that G retracts.

E3 responds:

Battery, 1/sp I, u II, E 3 I, e 2 I, 5/zh III, 115 ww I, v III, h III, earth.

E3 connects itself.

Earth, 5/h III, v III, ww I, zh III, 1/e 3 I, E 3 II, 5/g III, P, battery.

(23) Third closure. 120

J again responds. U retracts. St responds.

Battery, 1/St I, g I, u I, p I, 5/zh III, ww I, v III, h III, earth.

E2 retracts, because 5/g III at rest and 5/st III opens the holding current for E 2 II.

The following relays are energized: Ab, J, H, Z1, ZH, WW (JC) P, St, E3.

This is the same condition as during the 130

first closure only that E3 is energized instead of E1.

(24) With the succeeding impulses the condition at the end of 23 occurs with the "make" of the current after odd figures with the difference that E5 or E7 is energized and with the current "making" after even figures, the condition at the end of 21 is established with the difference that E4, E6 or E8 is energized instead of E2. During the 10 7th "make" the following relays are energized:

Ab, J, H, Z1, ZH, WW, (JC) P, St, E7.

(25) Coupling to subscriber's line "17".

15 As J remains energized, i. e. U or G no longer responds, 1/JC retracts after a period of retraction.

The relay K responds.

20 Battery, 6/K I, ww II, jc II, p III, 5/v III, h III, earth.

K connects itself.

Battery, 6/K II, k II, u III, h IV, earth.

25 2/k1 and 2/k II switch through the speaking wires. 7/k III closes the energizing circuit for the line relay 7/T 17.

Earth, 7/k III, e 7 III, T 17 I, z1 III, ww III, V, battery.

V and T 17 respond. V releases the selector and T 17 connects the subscriber's loop 30 to the speaking connecting line.

(26) Release of the selector.

5/v I short circuits P. When P retracts the holding circuits for E7, G or St, Z1, ZH and WW are opened by 5/p II (retracted) 35 and 5/v III (energized). Thus V also becomes de-energized and retracts after a certain time and with 5/v III makes the selector again ready for reception.

(27) The holding circuit for T 17 is closed over 3/t 17 II:

40 Battery, 3/T 17 II, t 17 II, 4/d IV, ab II, D, h II earth.

D responds. 4/d 1V opens the short circuit over 4/Ab I, which also responds if it 45 had retracted since the retraction of JC. 4/ab II short circuits D, which again retracts. Condition after the selector is cut off.

Following relays are energized: J, H, T 17, Ab.

50 (28) Ringing.

The operator in the main exchange puts the connecting plug into the speaking jack VKL. Earth therefore remains connected to the b wire over the relay B. Then she withdraws the selecting plug from the jack WKL. The change of plug has no influence on the sub-exchange. Then the operator sends out alternating current by throwing the ringing key R. The relay J is not released by 60 the alternating current. In the community station the ringing current energizes the relay W.

3/w II energizes the ringing relay N. 2/n II opens the branch to the choke. 3/n I and 65 3/n III bridge the condensers C1 and C2, so

that the ringing current from the main exchange flows direct for ringing the subscriber's station 17, as long as the operator has thrown the ringing key.

In the ringing pauses 3/n III connects the feed relay R and 2/n I connects the chokes Dr 1 I to the subscriber's line.

(29) Subscriber T 17 answered. In a ringing pause R responds.

Battery, 3/R, n III, subscriber's loop, n I, 75 choke Dr 1 I, earth.

2/r I, cuts off the battery from the a wire. This act deenergizes the supervisory signal SZ in the cord of the main exchange, whereat the operator recognizes the answer. 4/r 80 III opens the short circuit over D, which again responds without any consequences for the moment. When the subscriber replies the following relays are energized: J, H, K, T 17, D, Ab, K.

85 (30) Clearing signal to the exchange.

The subscriber "17" hangs up the receiver, R retracts, 4/r III short circuits D, which retracts without further consequences for the moment.

90 2/r I closes the circuit:

Battery, 2/r I, Dr 1 II, n II, k I, a wire, a spring of jack VKL, connecting plug visible signal SZ, earth.

(31) Release.

The release goes on exactly as with an outgoing connection, as in (9), (10) and (11).

Calling back into its own community exchange

100 Suppose subscriber 12 (not shown) wants subscriber 17.

(32) The subscriber takes up the receiver. The operations are as described in 1-6, inclusive. Upon answering over the answering plug the condition in the community exchange is thus:

Relays J, H, K, R, T 12, D, and Ab are energized.

In the call order 17, the operator recognizes that a recall or back ring is wanted.

110 (33) The operator requires the calling subscriber to hang up the receiver. R retracts.

4/r III short circuits D, which retracts 115 without further effect.

2/r I applies battery of 2/Dr 1 II to the a wire, whereupon the clearing signal appears in the main exchange. Now the operator knows that the calling subscriber has hung up the receiver. Now she inserts the selecting plug in the selecting jack WKL. The b wire is therefore grounded over the dial switch, whilst the b wire to the answering cord is interrupted through relay AT.

125 (34) Tens selection "1".

With the breaking of the impulse current, J retracts. U responds.

Earth, 2/j II, h 1, st1, U, battery.

6/u III opens the holding circuit for K

II, which retracts, in order not to disturb the numerical selection by the bridges lying behind the 2/k I and 2/k II. 1/uII lets E 1 and JC respond:

5 Battery, *sp* 1/u II, E 1 I, *p* I, 5/zh III, *v* III, *h* III, earth.

Circuit for JC:

Battery, *sp* I, 1/u II, JC II, 5/zh III, *v* III, *h* III, earth.

10 E 1 connects itself:

Earth, 5/h III, *v* III, *zh* III, *e* 1 I, E 1 II, 5/g III, P, battery.

P responds. During the succeeding closure of long duration in the dial switch, J responds. U retracts and as the closure lasts 15 a long time, JC also retracts.

The tens relay Z 1 responds:

Battery, 6/Z 1 I, *e* 1 II, *ww* II, *jc* II, *p* III, 5/v III, *h* III, earth.

20 Z 1 connects itself and energizes ZH.

Battery, 6/ZH, Z 1 II, *z* 1 I, 5/v III, *h* III, earth.

5/zh III opens the holding circuit for E 1, JC and P which retract. WW responds:

25 Battery, 5/WW, 6/zh I, *p* III, 5/v III, *h* III, earth.

WW connects itself over 5/ww I.

Condition after the tens selection.

Following relays are energized: J, H, T 12,

30 Ab, Z 1, ZH, WW.

(35) Units selection.

This condition is the same as at the commencement of (18), except that the relay T 12 and Ab are energized.

35 These relays have no influence on the succeeding units selection. The seventh closure of current creates the condition as described in 24.

Coupling of the line "17".

40 After a time, JC retracts. K and T 17 respond as described in (25).

Release of the selector as described under (25).

(36) After the end of the numerical selection, the operator inserts the connecting plug

45 in the connecting jack VKI and then withdraws the selecting plug.

(37) During the back ringing, both subscribers are called. The calling subscriber must only take up his receiver however, when the called subscriber has answered. In order to identify this condition, the call, during the back ringing connection, is effected by short interruptions, say every three seconds.

50 Should the calling subscriber place himself in circuit too soon, i. e. before the called subscriber has answered, the operator tells him to hang up his receiver and calls again.

The operator must therefore ask the first 60 replying subscriber what his telephone number is, in order to ascertain whether it is the called subscriber. In view of the small number of back ringing connections, this method of working should be permissible. In ex- 65 change with larger batteries (24 volt accumu-

lators) the call and the cutting off of the call may take place absolutely automatically by using a special cord for ring back connections in conjunction with a three-seconds ringing device. The clearing signal in the connecting cord disappears when one of the subscribers takes up his receiver and only appears again when both have hung up.

(38) Release.

When after both subscribers have hung up their receivers, the operator releases the connection by withdrawing the plug, the releasing action continues quite normally. (Section 9 and figure.) If by an oversight the connections were released too soon, both 80 subscribers not having hung up their receivers, J, H and K retract, but as R is energized, the relays T, AB and D remain energized. The ringing signal in the exchange appears over r1 (energized) and k I (retracted). The 85 mutual connection between the two subscribers is thus not disturbed. By plugging once more in the exchange, H and K again respond.

Outgoing call from a coin box instrument

90 The T relays of lines going to coin box instruments are taken to battery over the relay M. As soon as the locking circuit of the T relay is closed over D and Ab, relay M is operated and inserts the high resistance 2/Wi 95 in the calling circuit to the main exchange. Relay AR at the main exchange cannot be operated over the resistance 2/Wi. Hence only the coin box instrument calling relay MAR is energized, and the coin box instrument call indicator MASZ is operated over 100 earth, ar II, mar II to indicate the call. In this case the operator may only establish the connection after payment. The current that does not operate the relay AR is determined 105 by the resistance of the line. The establishment of the connection and the release of the group take place in the same manner as for an ordinary subscriber's line.

Wrong connection to a tens group that is blank

110 If during the tens selection a number is dialed that does not correspond to the group, for example 30, 40, 50, etc., the relay Sp is 115 operated over 6/e ³⁻¹⁰ II instead of the tens relays Z1 or Z2. The contact 1/sp I is opened and thereby disconnects the chain of E relays. Therefore a succeeding numerical selection has no effect on the selecting device and the 120 relay Sp remains energized. The contact 3/sp II closes the following circuit:

Battery, 3/Dr 2, *sp* II, busy relay 4/Bes, bes II, earth. The busy relay begins to buzz and this buzzer tone reaches the a-lead:

Earth, 4/bes II, Bes, *sp* II, a-lead to the main exchange.

125 This busy signal notifies the operator at the main exchange of her error and she withdraws the plug from the jack. Thereby the 130

relay J is deenergized at the sub-exchange and the sub-exchange releases in the ordinary manner.

5 *Selecting a subscriber's line that is not connected up*

The subscribers' numbers are so distributed that the number of subscribers connected to each tens group is the same. Hence for 14 lines the numbers 11 and 21, 12 and 22 up to 17 and 27 are used. The line relays for the unused lines 18 and 28 to 10 and 20 are not installed, in order to reduce to a minimum the apparatus at the sub-exchange. The contacts e III of the selecting relays E for the not connected up numbers are combined and are taken to the relay Sp. These are the contacts e 8 III, e 9 III, e 10 III in field 7 of the drawing. If during the numerical selection 15 one of the three relays E 8, E 9, or E 10 be energized, the relay Sp is operated, and this 20 has the same result as that described for a wrong tens selection.

What is claimed is:

- 25 1. In a telephone system wherein subscribers' lines terminating in a sub-exchange are arranged to be connected to a main exchange trunk line terminating in an operator's position at the main exchange and arranged to signal the operator thereat responsive to the initiation of a call, means for maintaining the calling subscriber's line in operative connection with said trunk line after the calling subscriber replaces his receiver in response to such request by the operator when calling a local subscriber, means in the sub-exchange controlled by impulses sent over said same trunk line from the operator's position for connecting a desired called subscriber's line to said trunk line, means controlled by the operator for signalling both the calling and called subscriber over said trunk line whereby the talking circuit between the calling and called lines is completed over a portion of said trunk line when both subscribers remove their receivers, and means controlled over said trunk line from the main exchange for releasing said connection after both subscribers have replaced their receivers.
- 40 2. In a telephone system, a main exchange, a sub-exchange, a trunk line comprising two talking conductors connecting said exchanges, two classes of subscribers' lines terminating in said sub-exchange, signals at the main exchange for designating the class of line calling, a relay in said sub-exchange common to all subscribers' lines of one class and operated whenever a subscriber in such class initiates a call, a circuit including contacts on said relay and one of said talking conductors for controlling the operation of said signals, and means in said sub-exchange controlled over said other talking conductor for opening said circuit whenever the call is answered.

3. In a telephone system, a main exchange, a sub-exchange, a trunk line connecting said exchanges, two classes of subscribers' lines terminating in said sub-exchange, signals at the main exchange controlled over only one of the talking conductors of said trunk line for designating the class of line calling, and a relay in said sub-exchange common to all subscribers' lines of one class for determining which one of said signals is to be operated, said relay operated whenever a subscriber of said one class initiates a call.

4. In a telephone system, a main exchange, a sub-exchange, a trunk line connecting said exchanges, two classes of subscribers' lines terminating in said sub-exchange, a line circuit for each subscriber's line for initiating a call over said trunk line, means common to and included in the said line circuits of all subscribers' lines of one class, signals at the main exchange controlled over said trunk line for designating the class of line calling, and means controlled by said first means for operating the signal corresponding to the class of the line which is calling.

5. In a telephone system wherein two classes of subscribers' lines terminating in a sub-exchange establish calls over the same trunk to a main exchange, signals at the main exchange controlled over said trunk line for designating the class of line calling, and a relay included in the individual line circuit of each subscriber's line of one class for determining which one of said signals will be operated, said relay common to all the subscribers' lines of said one class.

6. In a telephone system, a main exchange, a sub-exchange, a trunk line comprising only two talking conductors connecting said exchanges, a plurality of subscribers' lines terminating in said sub-exchange, a relay counting switch in said sub-exchange, means for transmitting impulses over only one of said conductors to set said switch in various positions corresponding to the telephone numbers of desired called subscribers, means operated in case the switch has been set in a position corresponding to one of said subscriber's lines for directly connecting said subscriber's line with said trunk line, a source of signalling current and a relay in said sub-exchange, and means for operating said relay to connect said source directly with the other of said conductors in case said switch has been set in a position which does not correspond to a working subscriber's telephone number.

7. In a telephone system, a main exchange, a sub-exchange, a trunk line comprising only two talking conductors connecting said exchanges, a plurality of subscribers' lines terminating in said sub-exchanges, a relay selective device in said sub-exchange, means for transmitting impulses from the main exchange over only one of said conductors for causing said switch to select and directly con-

nect the desired subscriber's line to said trunk line, and means operative in case the calling party dials a telephone number which does not correspond to a working subscriber's telephone number for causing said switch to connect a tone signal to the other of said conductors.

8. In a telephone system, a main exchange, a sub-exchange, a trunk line connecting said exchanges, a plurality of subscribers' lines terminating in said sub-exchange, a relay selective switch in the sub-exchange, means responsive to a calling party in the main exchange dialling the telephone number of one of said subscribers' lines over said trunk line for causing said switch to directly connect such subscriber's line to said trunk line, and means responsive in case the calling party dials a telephone number which does not correspond to any subscriber's telephone number for causing said switch to connect a special tone signal to said trunk line.

9. In a telephone system, a main exchange, a sub-exchange, a trunk line comprising only two talking conductors connecting said exchanges, a plurality of subscribers' lines terminating in said sub-exchange, a relay counting switch in said sub-exchange, an impulsing relay in said sub-exchange connected to one of said conductors, means for transmitting impulses over said one conductor to said relay, means controlled by said relay responsive to the receipt of said impulses for setting said switch in a position corresponding to the telephone number of the desired called subscriber, means controlled by said switch in operated position in case said switch has been operated to a position corresponding to a working subscriber's line for directly connecting such subscriber's line with said trunk line, a source of signalling current and a signalling relay in the sub-exchange, means for operating said signalling relay to connect said source with said other conductor in case said switch has been set in a position which does not correspond to a working subscriber's line, and means for controlling said impulsing relay over said first conductor to release the operated apparatus in the sub-exchange.

50 In witness whereof, I hereunto subscribe my name this 24th day of May, A. D. 1928.

FRITZ APPELIUS.
